(57) **CLAIM**

The ornamental design for display for a sewing machine, as shown and described.

DESCRIPTION

FIG. 1 is a front view of a display for a sewing machine;
FIG. 2 is a left-side view thereof;

FIG. 3 is a top view thereof;

FIG. 4 is a perspective view thereof; and,

FIG. 5 is an expanded view of the display of FIG. 1.

The broken lines define the bounds of the design but do not form part of the claimed design.
